(57) **CLAIM**

(**) Term: **14 Years**

The ornamental design for, an exterior surface configuration of a motorcycle front light assembly, as shown and described.

(21) Appl. No.: **29/133,402**

DESCRIPTION

(22) Filed: **Nov. 30, 2000**

FIG. 1 is a front view of an exterior surface configuration of a motorcycle front light assembly, showing our new design; FIG. 2 is a top plan view thereof; FIG. 3 is a right side elevational view thereof; FIG. 4 is a perspective view of thereof; and, FIG. 5 is a perspective view illustrating the present invention with the environment of the invention set forth in broken lines.

(51) LOC (7) Cl. **26-06**

Features shown in broken lines depict the environment and do not form part of the claimed design.

(52) U.S. Cl. **D26/28**
